(57) **CLAIM**

The ornamental design for a bag, as shown and described.

DESCRIPTION

1. Bag

FIG. 1.1 is a perspective view of a bag of the claimed design; FIG. 1.2 is a front elevational view of the bag shown in FIG. 1.1;

FIG. 1.3 is a back elevational view of the bag shown in FIG. 1.1;

FIG. 1.4 is a right elevational view of the bag shown in FIG. 1.1;

FIG. 1.5 is a left elevational view of the bag shown in FIG. 1.1;

FIG. 1.6 is a top plan view of the bag shown in FIG. 1.1; FIG. 1.7 is a bottom plan view of the bag shown in FIG. 1.1; and

FIG. 1.8 is an unfolded, perspective view of the bag shown in FIG. 1.1 in an alternate configuration.

The claimed design is shown in the figures by solid lines as well as by broken lines that represent stitching.
